UNITED STATES PATENT OFFICE

FRITZ GOSSLAU, OF BERLIN-CHARLOTTENBURG, GERMANY, ASSIGNOR TO SIEMENS & HALSKE, AKTIENGESELLSCHAFT OF SIEMENSSTADT, NEAR BERLIN, GERMANY, A CORPORATION OF GERMANY

FUEL PUMP

Application filed September 22, 1930, Serial No. 483,556, and in Germany October 1, 1929.

My invention relates to internal combustion engines, and more particularly to the feed pumps for the liquid fuel of such engines.

5 The object of my invention is to provide an improved valveless fuel pump of the type in which the quantity of fuel is regulated by rotatably adjusting the piston of the pump.

An embodiment of my invention is illustrated in the drawing affixed to my specification and forming a part thereof. In this drawing:

10 Fig. 1 represents a fuel pump for the airless injection of fuel into a Diesel engine, in longitudinal section, and

15 Fig. 2 a cross-section of a detail of said pump along line A—B of Fig. 1.

Referring to the drawing it will be seen that the pump has no intake valve. The fuel is supplied into pump chamber 4 from the supply duct 1 through the port 2, so long as this port is uncovered by piston 3. The fuel is delivered upwardly, as soon as the piston 3 on its upward stroke covers the port 2 and separates the pressure chamber 4 from supply duct 1. When the required delivery pressure has been attained in the compression chamber, the spring-controlled valve 5 opens and the fuel is delivered to the engine cylinder by a pipe not shown in the drawing.

Movement is imparted to the piston 3 by a cam 7, keyed to the shaft 6, through a tappet or plunger 8 provided with an anti-friction roller. The quantity of fuel to be delivered may be regulated by rotatably adjusting the piston 3. For this purpose the head of the piston is not flat, but spirally curved so that the time during which the piston 3 covers the inlet opening 2 varies according to the adjusted angular position of the piston. The piston 3 can be rotatably adjusted by means of a rack 9 engaging the pinion 10 mounted on the regulating sleeve 11. The sleeve is at its lower end provided with two slots 12 in which are located the two ends of a transverse bar 13, fixed in the piston rod. In the hitherto disclosed designs of such pumps the movable parts of the pump are arranged to be withdrawn from the bot-

tom of the pump casing after the cam shaft has been removed.

For many purposes it is, however, undesirable to remove the pump from below, for instance in internal combustion engines with 55 radially arranged cylinders in which the fuel pumps are likewise located radially in a single plane.

The object of my invention is to provide a fuel pump of this type whose operating parts 60 may easily be removed through the top of the casing. I attain this by connecting the pump piston 3 with the tappet or plunger 8 by means of a bayonet joint.

Referring more particularly to Fig. 2 of 65 the drawing it will be observed that the foot 15 of the piston 3 is of oblong shape corresponding with the shape of a slot 14 in the top of tappet 8. By turning the piston 3 its foot 15 can be set to register with the opening 14 and 70 be passed through it into a low chamber in the tappet, whereupon it may be locked by setting it at an angle, preferably of 90°, to the slot. The uncoupling of the two parts is effected in the reverse way in a very simple manner.

According to my invention the lower part of the regulating sleeve 11 in which the slots 12 are provided is contracted sufficiently to permit the location of the two ends of the transverse bar 13 of the piston rod 3 within 80 the inner diameter of the remaining portion of the sleeve, so that the bar can pass through sleeve 11 when the piston and the barrel are withdrawn upwardly.

If a breakdown occurs in a fuel pump of 85 this construction the pump may easily be withdrawn toward the top, for the purpose of repairs. To effect this the valve box in which the delivery valve 5 is housed is first removed. The pump piston 3 is then turned until its 90 foot registers with the slot 14 in the tappet. By unscrewing the screw 16 which locks the barrel 17 in the housing, the piston 3 together with the barrel 17 may then be lifted out through the top of the casing.

95 I claim as my invention:

A fuel pump having a casing, a stationary piston barrel and a reciprocating piston disposed therein, and having means for varying the amount of fuel delivered by varying its 100

angular position in the barrel, a regulating sleeve rotatably adjustable in the casing and containing said barrel and piston, said sleeve being contracted at its lower end to substantially the diameter of said barrel, and having diametrically opposite longitudinal slots in the contracted portion and a transverse bar fixed in said piston and engaging said slots with its free ends, for coupling said piston with said sleeve to partake in the rotary adjustments of the latter for adjusting the amount of fuel delivered by said piston, said bar having a length not greater than the inner diameter of said sleeve to permit the removal of said barrel and piston through the upper end of said sleeve and the outer end of said casing.

In testimony whereof I affix my signature.
FRITZ GOSSLAU.
